UNITED STATES PATENT OFFICE

CHARLES J. WHITE, OF NEW BRITAIN, CONNECTICUT.

SPRING-CLASP.

SPECIFICATION forming part of Letters Patent No. 380,154, dated March 27, 1888.

Application filed September 15, 1887. Serial No. 249,807. (No model.)

To all whom it may concern.

Be it known that I, CHARLES J. WHITE, a citizen of the United States, residing at New Britain, in the county of Hartford and State 5 of Connecticut, have invented a new and useful Clasp and Ring for Supporting Hose or other Articles of Clothing, of which the following is a specification.

My invention relates to improvements in a 10 clasp and ring for supporting articles of clothing; and the objects of my improvements are, mainly, simplicity of construction, efficiency, and convenience in use.

In the accompanying drawings, Figure 1 is 15 a front elevation of my clasp and ring as applied to a garter or elastic band, and Fig. 2 is a side elevation of said clasp and ring on an enlarged scale.

A designates the ring, and B the clasp, the 20 latter consisting of the two spring-arms *a* *b* and slide *c*. The spring-arms are formed of a single piece of sheet metal doubled upon itself, with an eye, *d*, formed at the bend to receive and hold the ring *A*, as shown. The arm *a* 25 terminates in a curved bend in the form of a **U**, immediately above which there is a larger bend, *e*. The other arm, *b*, is substantially straight, except at its jaw *f*, Fig. 2, where it is bent toward the arm *a* at substantially right 30 angles. This angular jaw *f* comes just inside of the terminal bend in the arm *a*, as shown. The slide *c*, when in the position illustrated, holds the jaws of the spring-arms in place; but when it is moved up toward the ring *A* the 35 proper distance the arms will spring open.

The ring *A* can be attached to any band or support with the clasp in a pendent position convenient for the required use. As shown, the ring is applied to the ends of a garter or 40 elastic band for encircling the leg. When so

worn, the top edge of the stocking can be secured within the clasp to support it. If the stockings are longer than is necessary in order to meet the clasp, the surplus top can be rolled up within the bend *e* and the jaws be made 45 to take hold of the stocking at any desired point below the top edge.

The jaw *f*, bent as shown and coming just inside of the bend on the end of the arm *a*, so deflects the fabric as to give a firm hold thereon, and the construction is very simple and inexpensive. The ring and body of the arms form a flat and smooth connection between the elastic band and the hose, and one that will give the wearer no inconvenience. 55

I am aware that prior patents show clamps or holders consisting of spring-jaws formed of a single piece of metal doubled upon itself and embracing a ring at the bent end, and I hereby disclaim the same. 60

I claim as my invention—

1. The herein-described clasp, having holding jaws, and immediately above said jaws the bend *e*, for receiving surplus portions of the article held by said clasp, and above said 65 bend straight portions with the slide *c* fitted thereto, substantially as described.

2. The herein-described clasp, consisting of spring-arms formed of a single flat strip of sheet metal doubled upon itself and having at 70 the termination of the longer arm the **U**-shaped bend, and the angular jaw *f* on the companion arm just above said bend, and the slide *c* on the body of said arms, substantially as described, and for the purpose specified.

CHAS. J. WHITE.
